Attorney

UNITED STATES PATENT OFFICE.

WALTER Z. MURRAY, OF RICHMOND, VIRGINIA.

ROLL-HOLDER.

1,398,646.

Specification of Letters Patent. Patented Nov. 29, 1921.

Application filed July 21, 1921. Serial No. 486,627.

To all whom it may concern:

Be it known that I, WALTER Z. MURRAY, a citizen of the United States, residing at Richmond, in the county of Henrico and 5 State of Virginia, have invented a new and useful Roll-Holder, of which the following is a specification

This invention relates to roll holders, the primary object of the invention being to 10 provide a device of this character which will secure a roll in a manner to permit the same to revolve but prevent displacement of the roll from the holder.

Another object of the invention is to provide 15 a roll holder including arms, novel means being provided to support the arms in horizontal positions, at the will of the user.

Another object of the invention is to provide 20 means to permit the spool forming a part of the device, to be moved to a position whereby the roll may be removed.

With the foregoing and other objects in view which will appear as the description 25 proceeds, the invention resides in the combination and arrangement of parts and in the details of construction hereinafter described and claimed, it being understood that changes in the precise embodiment of 30 the invention herein disclosed, may be made within the scope of what is claimed, without departing from the spirit of the invention.

Referring to the drawing:—

Figure 1 is an elevational view of a roll 35 holder constructed in accordance with the present invention.

Fig. 2 is a sectional view taken on line 2—2 of Fig. 1, the spool forming a part of the roll holder being broken away to illustrate the connection between the roll holder 40 and spool.

Fig. 3 is a detail view disclosing the shoulder of the bracket members.

Referring to the drawing in detail, the 45 device includes a pair of brackets indicated by the reference character 5, each bracket including a length of metal apertured to receive the securing screw 6, by means of which the same may be secured to a supporting wall or other supporting surface.

The lower portion of each bracket is bent 50 upwardly and inwardly as at 7 to grip the rod 8 of the supporting rod, the connection

between the gripping portions of the brackets and the rod 8 being such as to permit 55 free movement of the supporting arms within the brackets.

As shown, a portion of each upwardly and inwardly bent section is cut away to provide a shoulder 9, which shoulders are designed to contact with the arms of the support, when the support is moved to a horizontal position, thereby holding the support in such position to permit a roll to be readily and easily applied to the spool. 65

The support is formed preferably of flexible metal and includes the arms 10 and 11 respectively, the arm 10 being provided with a right angled portion 12 which is curved outwardly as at 13, the extreme end 70 of the arm terminating in a right angled portion 14 which provides a hook or stop to prevent the spool 15 from being removed from the support.

The spool is formed preferably of metal 75 and is hollow to receive the ends of the arms 10 and 11, there being provided an opening in each end of the spool to admit the right angled ends of the arms. The right angled portion 16 forms a part of 80 the arm 11 and when a roll is to be removed from the support, the arm 11 is moved laterally to disengage the right angled portion 16 from the spool.

From the foregoing it will be seen that 85 if it is desired to remove a roll from the support, the arm 11 is disengaged, whereupon the spool 15 may be moved to a position as indicated by dotted lines in Fig. 2 of the drawing. When the spool is in this 90 position, it will be readily seen that the roll will fall therefrom.

In the event that the arm 11 should become accidentally disconnected from the spool 15, the roll could not fall from the 95 support, since it is necessary on the removal of the roll to manually move the spool 15 to a position as disclosed in dotted lines in Fig. 2.

It might be further stated that in the 100 event that the roll is to be supported in spaced relation with the supporting wall, the support in its entirety, may be moved to a position at right angles to the supporting wall, where the same may be shifted 105 laterally to cause one of the arms to contact

with the shoulder of the bracket associated therewith, whereupon the arms are held in such position.

Having thus described the invention, what is claimed as new is:—

1. A roll holder including a pair of brackets, each bracket having a gripping member and having a shoulder disposed adjacent thereto, a movable support including 10 a rod having arms formed at its ends, one of said arms extending inwardly and having an outwardly curved portion terminating in a right angled end, a spool supported on the arms, and the opposite arm having a 15 right angled end to be positioned in the opposite end of the spool.
2. A roll holder including a pair of brackets,

ets, a support including a rod, means for connecting the rod to the brackets to permit of movement of the support with respect to 20 the brackets, said support having arms, each of said arms having a right angled end, a spool supported on the right angled ends, and means forming a part of one right angled end to secure the spool to the support. 25

In testimony that I claim the foregoing as my own, I have hereto affixed my signature in the presence of two witnesses.

WALTER Z. MURRAY.
